FIBER SCOURING AND WASHING BOWL

Edward H. Brooks, Jr., Portland, Maine, assignor
of fifty per cent to Elton H. Thompson, Port-
land, Maine

Application June 1, 1948, Serial No. 30,315

7 Claims. (Cl. 68—158)

1

This invention appertains to novel and useful improvements in devices for use in treating fibre.

An object of this invention is to convey fibre within an improved tank, convey the fibre over the top of a substantially flat top baffle plate or platform positioned in the tank, and the under portion or surface of said platform being concaved, creating an air chamber, and to circulate liquid within the tank continually above and below the said baffle plate or platform.

Another object of this invention is to supply a plurality of hoppers at the lower portion of the said tank or container and pivotally mount a plurality of baffle plates on the hoppers whereby the clearance or distance between the upper ends of the baffle plates and the lower surface of the platform may be selectively regulated in order to control the fluid flow characteristics within the tank.

Another object of this invention is to regulate the flow of fluid within the tank and accelerate the settling of refuse within the hoppers.

A still further object of this invention is to maintain a predetermined fluid level within the container and to relieve the accumulated refuse from the upper portion of the hoppers.

Another object of this invention is to place openings in the container or tank wherever it is deemed desirable and to attach a manifold to the openings whereby liquid may be withdrawn and if advisable, clarified or wasted.

Another object of this invention is to provide an apparatus for treating stock which includes introducing fibre stock into the upper portion of a liquid cleansing agent container and on the upper surface thereof, conveying the liquid and the major portion of the stock in order that the major portion of the stock may be removed from the upper surface of the liquid and then conveying the minor portion of the stock beneath the surface of a platform which defines a submerged air zone, withdrawing buoyant waste material from this zone and adjacent this zone and then conveying the minor portion of the stock to the surface of the liquid to again be processed.

Ancillary objects and features of novelty will become apparent to those skilled in the art, in following the description of the preferred form of the invention, illustrated in the accompanying drawings, wherein:

Figure 1 is a longitudinal sectional view of the preferred form of the invention;

Figure 2 is a sectional view of the invention taken on the line 2—2 of Figure 1;

2

Figure 3 is a perspective view of a portion of the tank showing particularly the baffle therein and a level valve in one wall of the tank;

Figure 4 is a sectional view taken substantially on the line 4—4 of Figure 1 and in the direction of the arrows;

Figure 5 is a perspective view of a portion of the manifold associated with the outlet in the tank;

10 Figure 6 is an enlarged fragmentary detail of construction showing the connection of a means for actuating all of the baffle plates; and,

Figure 7 is a fragmentary perspective view illustrating a sealing member applied at each end of the pivoted baffle plates.

Various methods and means for treating fibre such as scouring, cleaning and the like are well known in the art. It is one of the prime purposes of the invention to supply an improved tank with various appurtenances contiguous to the tank for rendering the treating process economical yet satisfactory.

The present invention is a continuation-in-part of copending application Serial No. 683,204 now Patent Number 2,533,218 issued December 12, 1950.

In the treatment of fibre of various types it is necessary if not most desirable, to utilize the usual liquid cleansing material at a temperature ranging from 70° F. to 180° F. depending on the type of material being treated. Accordingly, it is one of the purposes of the present invention to render the treating operation of fibre more economical by means of maintaining some of the heat of the liquid within that liquid through the utility of a closure 8 shown in Figure 3. This closure rests on and may be secured to the tank or cleansing liquid container 10, covering the rollers 7 and 9 which are suitably mounted in juxtaposition relative to the tank. These rollers are identical to those shown and disclosed in application Serial No. 683,204, now Patent Number 2,533,218 issued December 12, 1950.

45 A pickup roller and other mechanism (un-
shown) is supplied at the exit portion of the tank or container 10 and is generally indicated at 5. This functions to pick up and discharge fibre from the top surface of the liquid within the container or tank.

The said tank which is generally indicated at 10 is used to maintain a fluid therein of any type, such as water, water mixed with a cleanser or the like. The said tank 10 has side walls 12 and 14 respectively with ends or end walls 16

and 18 connected therewith. The lower portion of the tank 10 is formed of a plurality of successive hoppers indicated at 20 which extend the entire width of the tank. If it is found desirable the said hoppers may taper to a substantially circular or rectangular opening of a width smaller than that of the tank. This of course is a matter of choice.

A plurality of such hoppers are supplied and at one end of the tank 10 there is an enlarged hopper 22. It is within the enlarged hopper that the pickup unit described in certain of the mentioned copending applications, is supplied at the top portion thereof.

Identical level stacks or valve cages 26 and 28 respectively are provided in the end walls 16 and 18. These valve cages communicate with the interior of the tank and a small tongue 30 extends angularly toward the interior of the tank partially covering screen openings 32 and 34 respectively. Stationary valve plates 36 and 38 respectively are attached to the floor or bottom of the cages 26 and 28 for cooperation with movable valve plates 40 and 42. Removable valve plates 40 and 42 have screws 44 and 46 secured thereto by any suitable conventional swivel connection and threaded portions or shanks of the screws are received in threaded apertures in the cages 26 and 28. This construction renders the valve plates 40 and 42 adjustable relative to the stationary plates.

Through the utility of the above described valve means a predetermined level of fluid may be maintained in the tank. Of course, outlets 48 and 50 are provided in each cage for overflow purposes and angularly extending plates 31 may be positioned over the openings 46 and 50, as is seen best in Figure 1.

A substantially flat top baffle plate or platform 52 extends longitudinally within the tank and has planar upper and lower surfaces substantially normal to the sides 12 and 14 thereof and is sealed to the sides 12 and 14. Any suitable means may be used for attachment of this platform 52 to the sides of the fluid container. It is within the purview of the present invention to adjustably mount the baffle 52 within the tank so that it may be selectively positioned relative to the vertical height of the said fluid container or tank 10. Conventional means may be used in this connection.

The platform or baffle 52 has angularly inclined extensions 54 and 56 extending therefrom which project toward the said hoppers and the said extensions 54 and 56 which are sealed to the sides 12 and 14 thereof, forming a concave section in the under portion or the bottom of the platform 52.

This concaved section defines an air zone or chamber which is submerged within the liquid cleanser in the container 10. The upper surface of the liquid in the container is a distance from the upper surface of the baffle or platform 52. Further, the air zone or chamber is beneath the baffle or platform 52.

As is seen in Figure 1, the hoppers 20 and 22 actually form the bottom portion of the tank 10 and the walls defining the hoppers have apexes 60 on which a baffle plate 62 is pivotally mounted through the medium of a conventional pivot pin. A similar construction is provided at each apex forming a bank of baffle plates 62.

Each baffle plate (see Figure 6) has opposed perches 64 and 65 thereon with suitable pins or stub shafts 66 extending therethrough. At-

tached to each of the perches 64 and 65 is a pitman rod or link 68 which connects to the next adjacent baffle plate thereby forming a continuous linkage. Thus, by revolving a crank

5 72 which is attached to one of the hinged pins 76 (mounting the baffles 62) the entire bank of baffle plates 62 may be selectively regulated. The said shaft or hinge pin 76 may be any one of the hinge pins which attach the baffle plates to 10 the apexes of the hopper walls. However, the shaft chosen must be attached firmly to the pertinent baffle plate 62 in order that the rotating movement of the crank 72 may be transmitted to pivotal movement of the baffle plate 15 62 associated therewith. It is necessary that the baffle plates 62 shall wipe the walls 12 and 14 in order to provide an effective seal. Thus, sealing members which are preferably resilient are attached to close marginal edges of each 20 baffle plate 62. The sealing member may be in the form of resilient (such as rubber) shoes 78 and may attach in any suitable conventional manner.

By pivotal actuation of the bank of baffle plates 25 62 the distance between the upper portions of the baffle plates 62 and the lower surface of the platform 52 may be selectively regulated. Thus, fluid flowing in the zone between the under surface of the platform 52 and the upper end portions 30 of the bank of baffle plates 62 may be regulated as to velocity and volume by increasing and decreasing the above mentioned distance.

A plurality of elongated openings 78 are supplied in the wall 14 and a screen or other fo- 35 raminous member 80 may be attached over these openings. It is seen by inspection of Figure 1 that the said openings 78 are positioned beneath the said baffle 52 but above the upper ends of the baffle plates 62. This construction is supplied 40 to drain a portion of the fluid within the tank 10 and to take the portion of fluid for removal in the vicinity of the fluid upper level but not at the upper level. The more buoyant waste products rise in and adjacent the air chamber or zone defined by the platform 52 and it is this portion of fluid which should be drained in order that this particular type of refuse may be removed. With respect to the products carried by the sub-surface of liquid (submerged beneath the main upper surface of the liquid), they may be reclaimed and processed further. For example, in using wool, wax and certain types of oils are obtained as by-products.

A plurality of spaced plates 77 are defined by 55 the spaced elongated openings 78 and the heads (see Figure 5) 84 are fitted in the elongated openings between the spaced plates. These heads form a portion of a manifold system for conducting fluid to a drain, sump or to a reclaiming apparatus, as desired. Branch conduits 86 connect the heads 84 with the main manifold pipe 88 and valves generally indicated at 90 are supplied in the branch conduits. A manually operative type valve is shown. However, it is apparent that all of the valves may be regulated by hydraulic, electrical or other means in order that each may be opened the same amount simultaneously. It will be noted at this point that the crank 72 may be removed in favor of an electrical or hydraulic type of actuation mechanism in order to control the bank of baffles, each of which is designated at 62.

Each of the hoppers 20 and 22 are supplied with valves at the egress portion thereof in order to relieve accumulated waste material. The valve

construction may be conventional if it is found desirable and it is preferable that a slider type valve be supplied since this type has been found economical and efficient. It is essential that these valves 92 be actuated rapidly in order that the refuse be discharged quickly. Of course, suitable grooves may be supplied in the lower portions of each hopper in order to accommodate the slider valves 92.

The operation of the present invention is as follows: Fibre stock of any description, depending on the desire of the user of the invention, is introduced by any suitable means such as through the conduit or duct 96 at one end of the tank or fluid container. The fibre is conveyed along with the upper portion of the liquid across the top of the tank by actuation of the rollers 7 and 9, mentioned above. Spacer plates 97 are attached to the sides 12 and 14 of the tank 10 in order to keep the revolving members independent of each other in operation. These plates 97 serve as splash guards and the upper surface of the liquid and the fibre is conveyed in this manner.

Due to the buoyancy of the fibre it floats on the upper surface of the liquid within the container and is constantly urged above the platform 52. The pickup roller or mechanism generally indicated at 5 removes the major portion of the fibre for further treatment. This further treatment may be the introduction into a second identical mechanism including a tank and all pertinent parts for further cleansing operations, if it is found desirable. The minor portion of the fibre settles with refuse slightly below the upper surface of the liquid in the container. There are two types of refuse which are present in the majority of fibre cleansing treatment operations. The first type has a density greater than one and falls to some of the various hoppers described above to be removed through the actuation of the slider valves 92. The second type of refuse has a density slightly less than one and is carried along with the circuitous travel of liquid to the air zone or chamber beneath the platform 52. The action of the rollers 7 and 9 constantly maintains a circuitous flow of fluid in the tank, extending both above and below the platform 52. The refuse which has a density very close to one is positioned adjacent but spaced from the under surface of the platform 52 to be drained or withdrawn through the medium of the valve-manifold construction herein described.

It is intended that all of the fibre be conducted from the tank in the initial pickup operation. However there is always a small or minor amount which is carried with the flow of fluid adjacent the under surface of the platform 52. This minor amount must be reclaimed or recirculated in order that practical efficiency in the operation of the invention be realized. Thus, it travels with the fluid and lighter refuse beneath the baffle or platform 52 to be again introduced as a portion of the upper surface materials due to the flow of fluid within the tank, created by the revolving members 7 and 9.

By regulation of the bank of baffle plates, each of which is indicated at 62, the volumetric flow beneath the platform 52 and the upper surfaces or edges of the baffle plates 62 is regulated. Thus, by changing the area of inlet of the traveling or circulating liquid between the initial baffle 62 and the bend 54 the volume of fluid per unit time may be regulated. Thus the speed is selectively regulated. Different types of material (fibres) require different settings of the bank of baffles 62.

and this bank of baffles must be regulated in order to realize maximum efficiency in the invention.

Since the fibre is transferred or conveyed across the top portion of the liquid within the container entirely by means of the rollers there is no occasion to objectionably twist or distort the individual fibres thus fouling the stock. Piling is materially reduced and for all practical purposes is obviated by such treatment of the fibre.

In this single cycle of operation is noted that there are two surfaces of liquid in the tank 10. The main or upper surface first carries all of the stock and the major portion thereof is picked up. The second surface is beneath the platform 52 and carries only a small but important portion of the stock which is reintroduced for recirculation to the upper liquid level or surface.

The operation of the device is extremely rapid in comparison to conventional cleansing operations on fibres. Therefore, it has been found by experimentation that efficiency is materially enhanced by introducing pre-soaked fibre at the ingress portion of the tank. In pre-wetting or soaking the fibre it is essential to the final product that agitation of the fibre is maintained at a minimum. The natural contour and curvature as well as condition of each strand or fibre is maintained as unaffected as possible. Thus, the wetted or soaked fibre is conveyed and treated as described above.

Having described the invention, what is claimed as new is:

1. For use in the process of treating fibre, a tank having a substantially open top, a substantially flat horizontal imperforate baffle positioned in said tank and extending longitudinally thereof, means for circulating fluid and fibre in said tank in a path over and below said baffle, said tank having an outlet immediately below said baffle and valve means associated with said outlet, hoppers forming the lower portion of said tank to collect refuse, and valves in said hoppers to relieve accumulated refuse, baffle plates pivoted to said hoppers and extending upwardly into the space between the tops of the hoppers and the horizontal baffle, means for pivotally moving each of said baffle plates, said plates terminating beneath said baffle to direct the flow of fluid beneath said baffle and to selectively regulate the clearance between the lower surface of said baffle and the upper ends of said baffle plates.

2. For use in the process of treating fibre, a tank having a substantially open top, a substantially flat horizontal imperforate baffle positioned in said tank and extending longitudinally thereof and having its sides connected to the sides of the tank, means for circulating fluid and fibre in said tank in a path over and below said baffle, said tank having an outlet immediately below said baffle and valve means associated with said outlet, hoppers forming the lower portion of said tank to collect refuse, and valves in said hoppers to relieve accumulated refuse, baffle plates pivoted to said hoppers and extending upwardly into the space between the tops of the hoppers and the horizontal baffle, means for pivotally moving each of said baffle plates, said plates terminating beneath said baffle to direct the flow of fluid beneath said baffle and to selectively regulate the clearance between the lower surface of said baffle and the upper ends of said baffle plates, and said outlet having a foraminous member constituting a strainer extending thereover.

3. A fibre treating apparatus comprising a tank having spaced side walls, means for accumulat-

ing refuse in the lower portion of the tank, manually operative slider valves in said means for relieving accumulated refuse, a substantially flat horizontal imperforate baffle positioned within said tank and having side edges fixed to said side walls and angularly inclined terminal portions directed toward the lower portion of the tank forming an air chamber beneath said flat baffle to accommodate some of the fibre, baffle plates pivoted beneath said baffle and extending upwardly toward the baffle, means for pivoting said baffle plates simultaneously, and means between the upper portions of said baffle plates and beneath said baffle for discharging liquid from the tank, said refuse accumulating means including downwardly extending sump chambers disposed below the terminal portions of the baffle.

4. A fibre treating apparatus comprising a tank having spaced side walls, means for accumulating refuse in the lower portion of the tank, manually operative slider valves in said means for relieving accumulated refuse, a substantially flat horizontal imperforate baffle positioned within said tank and having side edges fixed to said side walls and angularly inclined terminal portions directed toward the lower portion of the tank forming an air chamber beneath said baffle to accommodate some of the fibre, baffle plates pivoted beneath said baffle and extending upwardly toward the baffle, means for pivoting said baffle plates simultaneously, means between the upper portions of said baffle plates and beneath said baffle for discharging liquid from the tank, said last mentioned means including a plurality of openings in side walls of the tank having valves connected therewith, and a screen for straining the issuing fluid, said accumulating means comprising downwardly extending sump chambers below the terminal portions of the baffle.

5. A fibre treating apparatus comprising a tank having spaced side walls, means for accumulating refuse in the lower portion of the tank, manually operative slider valves in said means for relieving accumulated refuse, a substantially flat horizontal imperforate baffle positioned within said tank and having side edges fixed to said side walls and angularly inclined terminal portions directed toward the lower portion of the tank forming a chamber beneath said flat baffle to accommodate some of the fibre, baffle plates pivoted beneath said baffle and extending upwardly toward the baffle, means for pivoting said baffle plates simultaneously, means between the upper portions of said baffle plates and beneath said baffle for discharging liquid from the tank,

and level control valves positioned in each end of the said tank for maintaining the fluid in the tank at a predetermined level, said refuse accumulating means including sump chambers extending downwardly from the terminal portions of the baffles.

6. In a fibre treating apparatus, an elongated tank having spaced side walls and spaced end walls, a plurality of successive hoppers formed in the lower portion of the tank, means in the upper portion of the tank for propelling fibres longitudinally through the tank, a flat top horizontal platform having side edges secured against the side walls of the tank, said platform extending longitudinally of the tank over the hoppers and under the fibre propelling means and having downwardly inclined end portions, vertically extending baffles having lower ends pivoted at the juncture points of the hoppers, means connecting the baffles to pivot the same simultaneously, said side walls having openings therein below the platform and above the upper ends of the baffles, said end walls having openings therein disposed above the upper ends of the baffles and below the top of the platform, and valve means regulating the flow of liquid through the last named openings.

7. In a fibre treating apparatus including a tank having a liquid level, an air pocket forming member secured in the tank below the liquid level and having an open bottom and a flat upper horizontal wall, said apparatus being provided with fibre circulating means whereby fibres will pass into and through the air pocket formed by the member without contacting said upper wall.
